(57) **CLAIM**

The ornamental design for a reconfigurable second row seat for automotive vehicle, as shown and described.

DESCRIPTION

FIG. 1 is a front-perspective view of a reconfigurable second row seat for automotive vehicle, in a reclining position, of the new design;

FIG. 2 is a rear-perspective view thereof, in the reclining position;

FIG. 3 is a side view thereof, in the reclining position;

FIG. 4 is a front view thereof, in the reclining position;

FIG. 5 is a rear view thereof, in the reclining position;

FIG. 6 is a side view thereof, opposite that of FIG. 3, in the reclining position;

FIG. 7 is a top view thereof, in the reclining position;

FIG. 8 is a side view thereof, in an upright position;

FIG. 9 is a front view thereof, in the upright position;

FIG. 10 is a rear view thereof, in the upright position;

FIG. 11 is a side view thereof, opposite that of FIG. 8, in the upright position; and,

FIG. 12 is a top view thereof, in the upright position.

The broken and dashed lines are for environmental illustrative purposes only and form no part of the claimed design.

1 Claim, 12 Drawing Sheets
